UNITED STATES PATENT OFFICE.

HARRY L. MYERS, OF TOLEDO, OHIO, ASSIGNOR TO THE AMERICAN FLOOR SURFACING MACHINE COMPANY, OF TOLEDO, OHIO.

BASE GRINDING-MACHINE WHEEL.

Application filed June 28, 1927. Serial No. 202,062.

The present invention relates to an improved base grinding machine wheel of the type used for grinding, shaping and polishing terrazzo base portions, wainscoting, 5 walls, and stair work.

A particular type of a machine is employed for work of this class, the same being well known in the trade as the "American Base and Wall Polisher". This machine is of course characterized by a number of structural features and advantages. 10

Among other parts, it includes what is known as a base machine wheel; this being in the form of a substantially cylindrical 15 abrasive element which is adapted to be fastened by a retaining nut on the end of a driving spindle.

Incidentally, this abrasive element or grinding wheel is formed at its inner end 20 with a lined bore for passage of the screw threaded end of the spindle. At the opposite end it is formed with a socket to accommodate the retaining nut and to accommodate the socket wrench which is employed in applying and removing the nut. 25

The prominent thought here, is to provide a new form or embodiment of base grinding machine wheel of such construction as to provide a dependable and efficient 30 substitute for the old type of wheel.

The improved wheel possesses outstanding and structural advantages in that it is simple and inexpensive to construct, sturdy in construction, and a radical departure 35 from the present type of machine wheels universally used on base and wall polishing machines.

The structural differences serving to produce the alleged features of the novelty 40 and advantages will become quite evident from the following description and drawings.

In the drawings:—

Figure 1 is a central longitudinal section through an improved base grinding machine wheel constructed in accordance with the present invention. 45

Fig. 2 is an end elevation looking in a direction from left to right in Fig. 1.

Fig. 3 is a view like Fig. 1 showing the old style wheel and indicating full proportions in dotted lines, and diminished proportions in full lines in order to give configuration after it has worn or become practically useless. 50

Fig. 4 is a view like Fig. 3, showing the full and diminished proportions of the improved type of wheel as compared with the old type.

Considering now the device in detail, it will be observed that the reference character 5 represents a substantially cylindrical block or body, composed of a suitable abrasive to adapt it for grinding and polishing work. Firmly embedded in this body 65 5 is a lead core 6 which, in external configuration, is somewhat bullet-shaped. This bore is centrally located and has its reduced or tapered end 7 extending slightly beyond the longitudinal center of the abrasive block and terminating in spaced relation from the outer end 8 of this block. 70

The opposite end of this core is disposed flush with the inner end 9 of the block. The core is formed with a circumferential 75 anchoring or retaining rib 10. In addition, the core is formed with a smooth surfaced socket 11 terminating at its inner end in a reduced screw threaded counter-socket 12. At the juncture of the counter- 80 socket and the main socket, a hexagonal nut 13 is securely embedded or anchored in the core and has its screw threaded opening in alinement with these sockets.

It might be added here, that a core of this 85 type is susceptible of inexpensive manufacture in that it can be cast and turned to shape on a mandrel (not shown) whether or not the mandrel has a screw threaded end and whether or not the nut is placed on the 90 screw threaded end in a manner to allow a portion of the screw threaded end to project beyond the nut. When the core is thus formed on a nut equipped screw threaded mandrel, the projecting screw threaded end 95 of the mandrel leaves the screw threaded counter-socket 12 and the smooth portion of the mandrel, forms the smooth walled socket 11. The nut previously on the mandrel is 100 left embedded in the core after the core is removed from the mandrel.

Before further discussing this improved base wheel, attention is invited to Fig. 3, wherein it will be observed that the reference character 14 designates generally the 105 old style or type wheel.

As intimated at the outset of the description, this comprises a cylindrical block 15 having a metal lined bore 16 which will accommodate the customary driving spindle 110

(not shown). The screw threaded end of this spindle projects into a recess 17 which is formed in the outer end of the block. The purpose of the recess is to accommodate a retaining nut which abuts the shoulder 18 and which is placed in position and removed by a socket wrench.

The recess also accommodates the socket wrench. In order to appreciate the real 10 novelty of this invention, the old style wheel should be compared with the new style wheel particularly from a standpoint of wearing properties. The new wheel is a radical departure from the present type wheels universally used; aside from the adaptability, the life of it has been materially lengthened.

A more dependable coupling is afforded with the new type particularly by the presence of the embedded nut 12 and the counter- 20 socket for threaded connection with the extended end of the spindle.

Having thus described my invention, what I claim as new is:—

1. A base grinding machine wheel of the 25 character described comprising a body, a core

embedded centrally in said body, said core having a smooth surface socket terminating at its inner end in a screw threaded counter-socket, and a nut anchored in said core and disposed in spaced relation to said counter-socket.

2. As a new product of manufacture, a base grinding machine wheel comprising a grinding and polishing element in the form of a substantially cylindrical body of solid formation, a substantially bullet-shaped core embedded centrally in said body and having its tapered end spaced from the outer end of the body, and having its opposite end formed with flat and disposed flush with the inner end of the body, said core having a socket, the major portion of which embodies a smooth wall, the inner end of which is screw threaded, and a coupling and retaining nut anchored in said hole and having its screw threaded opening in alinement with said socket.

In testimony whereof I affix my signature:

HARRY L. MYERS.
